US00D938110S

(12) **United States Design Patent** (10) Patent No.: **US D938,110 S**
(45) Date of Patent: ** Dec. 7, 2021

(54) **FABRIC CARE APPLIANCE**

(71) Applicant: **WHIRLPOOL CORPORATION**,
Benton Harbor, MI (US)

(72) Inventors: **Kevin B. Ayers**, St. Joseph, MI (US);
Andrew C. Kubasiak, St. Joseph, MI (US); **Anna C. Schelling**, Stevensville, MI (US); **Mark W. Schulz**, Benton Harbor, MI (US)

(73) Assignee: **Whirlpool Corporation**, Benton Harbor, MI (US)

(**) Term: **15 Years**

(21) Appl. No.: **29/764,487**

(22) Filed: **Dec. 30, 2020**

CLAIM

The ornamental design for a fabric care appliance, as shown and described.

DESCRIPTION

FIG. 1 is a perspective view of a fabric care appliance according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

Dash-dot lines adjacent un-shaded areas represent bounds of the claimed design and form no part of the claimed design themselves.

1 Claim, 7 Drawing Sheets
